UNITED STATES PATENT OFFICE.

ERICH NIEMANN, OF CHARLOTTENBURG-BERLIN, GERMANY, ASSIGNOR TO A.-G. FÜR
HANDELS-UND INDUSTRIEWERTE GLARUS, OF GLARUS, SWITZERLAND.

SAFETY DEVICE FOR ABSORPTION REFRIGERATING MACHINES.

Application filed December 10, 1924, Serial No. 755,034, and in Germany May 3, 1924.

The invention refers to a safety device in refrigerating machines.

In the accompanying drawings—

Figure 1 shows by way of example a diagrammatic illustration of the invention.

Figure 2 is a detail view of the safety device.

The boiler K of an absorption machine is provided with a filling N, for example ammonia and water. This filling N is heated during the boiling period by the heating apparatus F, by means for example of petroleum, gas or the like. The gases thus produced escape through the piping B in the generally known manner to the condenser, separator and evaporator. After the close of the boiling period, cooling water is passed in the generally known manner from the main water supply pipe W through the water-regulating cock H₂, by means of the cooling-water supply pipe A, into the boiler, and here flows through the two cooling tubes R₁ and R₂, and is finally discharged through the water discharge pipe E.

Now in the case of the present invention a second water tube L (the tube for a fusible plug) is inserted for example in the upper cooling tube R₁, for example by being screwed into a covering sleeve M. By means of the separating sleeve V it is connected through the water cock H₁ directly with the main cooling water pipe.

The free end of this pipe L is supported in the cooling water tube R₁ and has a small bend at the end so that any jet of cooling water flowing out of this tube is directed straight against the wall of the tube R₁.

On to the end of the aforesaid water tube is screwed a fusible plug S, which is diagrammatically illustrated by itself in fuller detail in Figure 2. The fusible plug (see Figure 2) consists of a simple piece of tubing T, carrying a screw thread at one end. The other end of this tube is filled with a metallic alloy, such as bismuth solder. This alloy must in each case be so selected that it fuses at a predetermined temperature.

Now the safety device works in the following manner:—

Let the boiling period of the boiler K be terminated for example upon a temperature of 118° C. and a working pressure of eight atmospheres being reached. During the boiling period of course no cooling water

has flowed through the tubes R₁ and R₂, as during this period only the condenser and the separator are cooled. If from any cause the heating fails to be discontinued, an unintentional continuance of the boiling will take place. Consequently the temperature and the pressure in the boiler must rise higher, and according to the quantity and nature of the filling the explosion danger zone will be reached for example at a temperature of 200° C. and a pressure of 35 atmospheres. Now the alloy of the fusible plug is so selected that it fuses at 130° C., that is to say, long enough before the explosion danger zone is reached. As soon as the alloy in the fusible plug begins to melt, the water tube L becomes free and accordingly an intensive jet of cooling water spurts out of the tube L, which is subjected to the full supply pressure through the cock H₁, into the cooling water tube R₁, and flows away through R₂, also cooling this tube. By means of this cooling water jet the result is obtained that the boiler K, notwithstanding the uninterrupted further heating, is so intensively cooled down that not only is any further rise of temperature and pressure obviated but both are immediately reduced, that is to say, the temperature falls below 130° C. and the pressure drops sharply down at the same time. In consequence of this cooling setting in, all danger of explosion is completely obviated.

The advantages of this safety device in comparison with the constructions hitherto known obviously rest on the fact that the danger of explosion is obviated without any sort of mechanical apparatus being employed. The fusible plug may be in use for years without its melting point changing at all. By suitable choice of an alloy, such as bismuth solder, the risk is obviated of it being chemically changed, as for example by being attacked by the refrigerating medium. A further advantage of this invention appears in the fact that when the plug comes into operation no sort of loss occurs of the boiler contents, that is to say, of the refrigerating medium. A refilling or repairing by skilled workmen, or even returning the whole apparatus to the factory, is therefore saved. On the other hand anyone without previous experience would be able, simply by slackening the two sleeves V and M from

the tube L to unscrew the used fusible plug and insert a new one. This operation is as simple for example as changing an ordinary electrical fuse in electrical plant of the usual type.

5 The introduction of the tube L into the boiler K may of course be effected in a different form, for example by putting in a nest of cooling tubes expressly constructed 10 for this purpose. If there are two or more boilers combined in one absorption-machine then each of these boilers is to be secured by the insertion of a safety device according to the invention.

15 What I claim is:—

1. In an absorption refrigerating apparatus a boiler having a cooling medium passage, a tube inserted in said passage and spaced therefrom, a fusible element melting 20 at a temperature exceeding the highest normal working-temperature of the apparatus and closing one end of said tube, means for supplying a cooling medium to the other end of said tube.

2. In an absorption refrigerating appara-

tus a boiler having a cooling medium passage, a tube having at least one opening, said tube being inserted in said passage in a detachable way, a fusible element melting at a predetermined temperature inserted in said 30 opening and closing it, means for supplying a cooling medium in said tube.

3. In an absorption refrigerating apparatus a boiler having a cooling medium passage, a tube inserted in said passage having 35 at least one opening, a fusible element being inserted in said opening in a detachable way, means for supplying a cooling medium in said tube.

4. In an absorption refrigerating apparatus a boiler having a cooling medium passage, a tube inserted in said passage and spaced therefrom, said tube having at least one opening therein inclined to the walls of 40 said passage, a fusible element closing said opening and melting at a predetermined temperature, means for supplying a cooling medium under pressure in said tube.

ERICH NIEMANN.
